(57) **CLAIM**

The ornamental design for a knee rehabilitation apparatus, as shown and described.

DESCRIPTION

FIG. 1 is a front top right perspective view of a knee rehabilitation apparatus showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear top left perspective view thereof; and,

FIG. 9 is a front bottom right perspective view thereof.

The broken lines including the areas within them depict portions of the knee rehabilitation apparatus that form no part of the claimed design.
